FLY CASE

William N. Grandin, Amesbury, Mass.

Application July 6, 1940, Serial No. 344,265

1 Claim. (Cl. 43—32)

My invention relates to improvements in cases for fishing flies, the principal object in view being to provide a light-weight, inexpensive pocket case for carrying wet or dry flies so that neither the hooks, nor the delicate structure of the flies will be injured and which is especially adapted for carrying a large number of flies within a relatively small space so that access may be readily had thereto for selection as desired.

To the accomplishment of the above, and the subordinate objects presently appearing, a preferred embodiment of my invention has been illustrated in the accompanying drawings, set forth in detail in the succeeding description, and defined in the claim appended hereto.

In said drawings:

Figure 1 is a view in perspective of the preferred embodiment of my invention.

Figure 2 is a view in top plan with the cover plate removed and parts shown in section.

Figure 3 is a view in longitudinal section taken on the line 3—3 of Figure 2.

Figure 4 is a view in transverse section taken on the line 4—4 of Figure 3.

Figure 5 is a view in transverse section taken on the line 5—5 of Figure 3.

Figure 6 is a view in perspective of the dividing bar, and

Figure 7 is a view in perspective of one of the flights.

Referring to the drawings by numerals, in the illustrated embodiment thereof, the fly case of my invention comprises a container 1, of elongated, substantially rectangular form and having enlarged cylinder-like ends 2 for a purpose presently seen. Intermediate the ends 2 the container 1 is flat and comparatively shallow. The container 1 embodies a body portion 3 and a cover plate 4 hinged at one side edge thereof, as at 5, to one side 6 of the body portion and adapted to be latched in closed position by a suitable spring catch 7 engaging a notch 8 provided in the other side 9 of said container. The cover is provided with a door 10 fitting therein and preferably offset from the transverse center of the container toward one end thereof, said door being hinged, as at 11, to the cover plate 4 and being provided with a suitable friction latch 12 for coaction with one edge of said plate to yieldingly hold the door closed. The body portion 3 is preferably formed of light, strong, thin metal, and the cover plate 4 and door 10 of suitable composition material.

Within the ends 2 of the container 1 is a pair of cross-shafts 13 extending axially of the ends

and suitably journaled in the sides 6, 9, against end play. A longitudinally extending bar 14 with end bearings 15 through which the shafts 13 extend is provided in the container 1, centrally thereof, said shafts supporting the bar and the bar forming a dividing member for a purpose presently seen.

A pair of sprocket toothed wheels 16 are fixed on each shaft 13 adjacent opposite sides 6, 9, of the container 1, respectively. A pair of flexible sprocket bands 17, of any suitable material, at opposite sides of the container 1, respectively, connect the sprocket wheels 16 in pairs.

The sprocket bands 17 support cross flights 18 spaced equidistantly apart and each embodying a bar 19 of cork, or a similar material, and a backing bar 20 of thin metal having its ends suitably connected, as by rivets 21, to the pair of sprocket bands 17, respectively. One of the shafts 13 is extended through one side 6, or 9, as the case may be, of the container 1, and provided with a knurled knob 22 for rotating said shaft.

In the use of the described case, the flies 23 are attached to the bars 19 by inserting the hooks in one side of said bars with the remainder of the flies extending cross-wise thereof as shown in dotted lines in Figure 2. The wet and dry flies may be thus attached to the bars 19 upon opposite sides of the bar 14 so as to separate the same. The bar 14 also functions as a brace for the shafts 13. As will be apparent, the sprocket bands 17 and described flights 18 provide a conveyor that may be operated through the medium of the knob 22 to feed the flies past the door 10 in two separate displays for selection and detachment of the flies as desired. The cylindrical form of the ends 2 of the container 1 provide for adequate clearance between the flies 23 and the interior of the container 1 when said flies are moved around the shafts 13 under which operation, as will be clear, the flies project at different angles from the conveyor than when travelling between said shafts.

If desired, instead of using the door 10 for access to the interior of the container 1, the cover plate 4 may be unlatched and used to open the entire container.

Any suitable means may be provided on the shafts 13, such as collars 24, for preventing the bar 14 from creeping along the shafts.

The foregoing will, it is believed, suffice to impart a clear understanding of my invention without further explanation.

Manifestly the invention, as described, is susceptible of modification without departing from

the inventive concept, and right is herein reserved to such modifications as fall within the scope of the subjoined claim.

What I claim is:

A case for fishing flies comprising an elongated substantially rectangular container having an open top, a closure plate for said top detachably secured thereto, a pair of cross shafts journaled in said container at opposite ends of the latter, respectively, one manually rotatable from the outside of the container, an endless conveyor extending between said shafts comprising a pair of sprocket wheels fast on each shaft adjacent opposite ends thereof, respectively, a pair of sprocket bands upon opposite sides of 15 said container trained around said sprocket

wheels, and a plurality of cross flights extending between said bands and each including a cork strip into which the hooks of flies may be inserted, and a central bar extending between said shafts and forming a division indicating member whereby different kinds of flies attached to the flights upon opposite sides of the bar may be separated, said plate being provided with a small door therein for access to said flies without detaching said plate, the ends of the container being enlarged and substantially cylindrical to provide for clearance for the flies on the conveyor under travel of the latter around said shafts.

WILLIAM N. GRANDIN.
